LADY'S GARMENT

William Freedman, New York, N. Y., assignor to
Sport-Time Inc., New York, N. Y., a corporation
of New York

Application February 9, 1938, Serial No. 189,487

4 Claims.

(Cl. 2—70)

The present invention relates to ladies' garments, and more particularly to multi-piece sport ensembles for beach wear and the like.

An object of the invention is to provide a sport ensemble, having various pieces which can be arranged and assembled with ease, to produce different fashionable articles of dress or different attire effects.

A more specific object is to provide a skirt, which can be worn in detached combination with a short jacket to form an attractive sport ensemble therewith, which can be connected easily to said jacket to form a full length garment such as a beach coat, and which can be used as a cape.

To carry this object into effect, the jacket, (which is in the form of a bolero or Eton jacket cut square at the waist) and the skirt (which is open at the front) are provided with means for detachably fastening them together at the waist to form what would appear as a one piece beach coat, the skirt having means for girding it about the waist when unfastened from the jacket.

Another object is to provide an open front skirt, which when worn around the shoulders forms a modish cape with an upstanding collar, and which has skirt closing means at its waist line serving also as collar closing means in its cape transformation.

As another feature of the invention, the skirt piece has a series of button holes on its waist section through which corresponding buttons in the jacket waist may be slipped to form the full length garment above referred to, and through which a ribbon or cord may be threaded for tying the upper section of the skirt piece closely around the neck when said piece is used as a cape and when it is desired to obtain a different collar effect than is produced by the use of the waist closing means above referred to.

Various other objects, features and advantages of the invention will be apparent from the following description, and from an inspection of the accompanying drawings, in which,

Fig. 1 is a perspective of the front of a sport ensemble consisting of a playsuit, and an open front skirt girdled around the wearer's waist and over said playsuit.

Fig. 2 is a perspective of the front of a sport ensemble, which in addition to the garment pieces shown in Fig. 1, includes a jacket detached with respect to the skirt.

Fig. 3 is a perspective of the front of a sport ensemble, in which the jacket and the skirt are interconnected to form a beach coat.

Fig. 4 is a front perspective view of the skirt piece converted into a cape, with the waist fastening means serving as a collar fastening means in its cape transformation.

Fig. 5 is a front perspective view of the skirt piece converted into a cape, and having a ribbon or cord at its upper end for tying the cape around the wearer's neck.

Fig. 6 is a perspective of the rear view of the jacket,

Fig. 7 is a plan of the skirt piece spread in open position, and

Figs. 8 and 9 are detailed sections on an enlarged scale, taken on lines 8—8 and 9—9 respectively of Fig. 7, and showing various thicknesses on exaggerated scale for purposes of clearness.

Referring to the drawings, one unit of the sport ensemble comprises a playsuit A, desirably of conventional one piece construction, and consisting of shorts 10 and a halter top 11.

The ensemble also includes a garment piece B, which may be girded around the wearer's waist and over the playsuit A to form an open front beach skirt as shown in Figs. 1 and 2, or which may be used as a cape as shown in Figs. 4 and 5. The material of this garment piece B is straight cut so that it will drape gracefully downwardly over the wearer's body when used as a skirt, and is desirably made from a pair of rectangular panels 12 seamed together at 13 as shown in Fig. 7. Near the upper end of the garment piece B is a transverse strip-like shirred section 14, desirably formed in the well-known manner by a series of parallel gathering stitches 15, and extending the full width of the garment piece B, so that said piece will be substantially in the shape of an isosceles trapezoid with the wider section at the bottom. The garment piece B is desirably provided with a hem 16 at the bottom 40 and hems 17 at the sides.

At the upper end of the garment piece B is a waist band 18, which desirably comprises a fabric strip doubled lengthwise thereof, and having the lower ends infolded and connected to the upper end of the shirred section 14 by stitches 18a, and which has its upper fold edge stitched at 19 to flatten said band. In order to fasten the garment piece B either around the waist when used as a skirt, or around the neck when used as a cape, it is provided with a series of buttons 20 on one side of the upper end of said garment piece, and a corresponding number of button loops 21 on the opposite side adapted to be slipped over said buttons. These button loops 21 desirably con-

sist of a series of folded cords, having the inner ends of some of them extending into the open end of the waist band 18 and stitched thereto, and having the inner ends of the other cords extending through an opening 23 in the fold edge of one of the side hems 17 at a section thereof opposite the Shirred section 14, and fastened thereto by stitching 24 passing through said cords and through infolded sections 25 of said hem formed on opposite sides of said opening, as shown in Fig. 8.

The waist band 18 is also provided with a series of spaced button holes 27 for the purpose hereinafter set forth, the end button holes 27a being disposed closely adjacent the ends of said band.

When the garment piece B is worn as a skirt, this piece is buttoned around the wearer's waist by slipping the buttons 20 through the corresponding button loops 21 as shown in Fig. 1. When so worn, the shirred section 14 of the garment piece will extend substantially to the wearer's hip-bone, so that the upper portion of the skirt will fit snugly around the waist, while the portion of the garment therebelow will have a full graceful flare towards the bottom hem 16 of the garment piece, to obtain the so-called "dirndl" effect.

The sport ensemble also includes a waist length open front jacket C, cut square at the waist 30, shaped in substantially the form of a bolero or Eton jacket, and desirably provided with a bottom hem to form a waistband 31. The waistband 31 of the jacket is co-extensive in length with that of the waistband 18 of the garment piece B, and has a series of buttons 32 secured on the outer side thereof and spaced to correspond with the spacing of the button holes 27 on said waistband 18. By means of this construction, the jacket C may be stylishly worn loosely over the halter top 11 of the playsuit A, detached from the skirt B as shown in Fig. 2, or may be buttoned to the upper end of the skirt B by slipping the buttons 32 through the button holes 27 to form a beach coat as shown in Fig. 3. This coat may be worn opened as shown in Fig. 3, or may be buttoned at the waist by means of the buttons 20 and the button loops 21, so that the opened coat will be converted into somewhat of a partially closed overdress, formfitting around the waist.

The buttons 32 are desirably covered with the same material as that from which the jacket garment is made, so that they will add to the ornamental appearance of the jacket, even when detached from the skirt. When the jacket is buttoned to the skirt, the button connection between said jacket and said skirt is not obvious, the buttons appearing as ornamentations, thereby giving to the resultant coat the appearance of being made of one piece.

The garment piece B may be used as a cape as shown in Fig. 4, the buttons 20 and the button loops 21 serving to fasten the upper portion of said piece around the neck in this converted form of the garment piece. It should be noted that the shirred section 14 of the garment piece B imparts a substantial amount of rigidity to said section, so that when said piece is worn as a cape as shown in Fig. 4, the portion of said garment piece above the lower edge of the shirred section 14 forms an upstanding collar 35. If it is desired to close the collar 35 snugly around the wearer's neck, instead of using the collar fastening means 20 and 21, a string or ribbon 36 may be threaded

through the button holes 27, and the ends of said ribbon tied together as shown in Fig. 5.

The different pieces of the sport ensemble are made of the same or matching material such as floral cretonne, and as already noted may be changed about, and may be combined in various manners set forth, or may be used singularly to obtain different fashionable outfits or to produce different attire effects. Furthermore, the garment piece B may be provided with a series of fastening means, (not shown) along its full length at the opposed edges thereof to form a skirt adapted for more formal wear. Also the jacket may be provided with a series of fastening means in the front so that it may be converted into the closed bodice of a dress when connected to the skirt.

It should be noted that although the skirt and the jacket are shown in combination with a playsuit, that as far as certain aspects of the invention are concerned, this playsuit may be eliminated.

It should also be noted that the shirring piece at section 14 of the garment piece B may be replaced by tiny pleats, without departing from the broader aspects of the invention.

Furthermore, as far as certain aspects of the invention are concerned, the button holes 27 and the corresponding buttons 32 as well as the buttons 20 and the loops 21 may be replaced by hooks and eyes, hookless fasteners or any other garment fastening means.

As many changes could be made in the above construction, and many apparently widely different embodiments of this invention could be made without departing from the scope of the claims, it is intended that all matter contained in the above description or shown in the accompanying drawings, shall be interpreted as illustrative and not in a limited sense.

Having thus described my invention, what I claim as new and desire to secure by Letters Patent is:

1. A lady's garment ensemble including a waist length jacket piece cut square at the bottom, and having a series of buttons on the outer side thereof spaced along its waist line, and a garment piece of the same material as said jacket piece, substantially in the shape of an isosceles trapezoid, with the greater width at the bottom, said garment piece having a waist band at its upper end and means near said end for girdling said garment piece around the wearer's waist to form an open front skirt, said waist band being substantially the same length as the waist line of said jacket piece and having a series of button holes spaced therealong to correspond to the spacing of said buttons, said two garment pieces being open at their front throughout the entire length thereof, being adapted to be used in detached combination as a fashionable ensemble, and said jacket buttons being adapted to be slipped through said corresponding button holes to combine said pieces into a full length coat.

2. A lady's article of attire comprising a garment piece substantially in the form of an isosceles trapezoid and having a strip-like section near its upper narrower end gathered the full width of said garment piece, a waistband connected to the upper edge of said gathered section, and substantially co-extensive in length with that of said gathered section, and means for fastening the upper opposed end sections of said garment piece together, whereby said garment piece may be fastened around a wearer's waist to form a skirt.

5 said garment piece being adapted to be used as a
cape, and said gathered section having substan-
tial rigidity whereby said gathered section and
said waistband in cape transformation form an
upstanding collar, said waistband having a series
of spaced openings along the length thereof
through which corresponding buttons on an upper
dress section may be slipped to form a full length
garment, or through which a cord or ribbon may
10 be threaded to tie the said collar around the wearer's
neck in cape transformation.
15 3. A lady's garment ensemble including a waist
length jacket piece cut square at the bottom and
having a series of buttons on the outer side
thereof spaced along its waist line, and a garment
piece of the same material as said jacket piece,
substantially in the shape of an isosceles trape-
zoid, with a greater width at the bottom, said
latter garment piece having a waist band of
20 thicker material at its upper end, means near
said end for girdling said garment piece around
the wearer's waist to form an open front skirt,
said waist band being substantially of the same
length as the waist line of said jacket piece and
25 having a series of button holes spaced therealong
to correspond with the spacing of said buttons,
said two garment pieces being open at their front
throughout the entire length thereof, being
adapted to be used in detached combination as a

fashionable ensemble, said jacket buttons being
adapted to be slipped through said corresponding
button holes to combine said pieces into a full
length coat, and said garment piece being adapted
to be used as a cape, the upper or waist band por-
tion thereof having substantial rigidity whereby
in cape transformation it forms an upstanding
collar, through the button holes of which a cord
or ribbon may be threaded to tie the said collar
around the wearer's neck in cape transformation. 10
15 4. A lady's article of attire comprising a gar-
ment piece substantially in the form of an isos-
celes trapezoid, a waistband connected to and
extending the length of the upper edge of said
piece and means for fastening the upper opposed
ends of said waistband together, whereby said
garment piece may be fastened around a wearer's
waist to form a skirt, said garment piece being
adapted to be used as a cape, the upper portion
thereof having substantial rigidity, whereby in 20
cape transformation it forms an upstanding col-
lar, said waistband having a series of spaced open-
ings along the length thereof through which cor-
responding buttons on an upper dress section may
be slipped to form a full length garment, or 25
through which a cord or ribbon may be threaded
to tie the said collar around the wearer's neck in cape
transformation.

WILLIAM FREEDMAN.
